COMBINED WORKBENCH, CABINET, AND
OVERHEAD TROLLEY SUPPORT

Howard Orion Miller, Chicago, Ill.

Application September 22, 1952, Serial No. 21,541

Term of patent 14 years

(Cl. D93—2)

To all whom it may concern:

Be it known that I, Howard Orion Miller, a citizen of the United States of America, residing at Chicago, in the county of Cook, State of Illinois, have invented a new, original, and ornamental Design for a Combined Workbench, Cabinet, and Overhead Trolley Support, of which the following is a specification, reference being had to the accompanying drawing, forming a part hereof.

Fig. 1 is a perspective view of a combined workbench, cabinet, and overhead trolley support embodying my new design;

Fig. 2 is a top plan view;

Fig. 3 is a front elevational view thereof, and Figs. 4 and 5 are, respectively, views of the opposite ends of the same.

I claim:

The ornamental design for a combined work-

bench, cabinet, and overhead trolley support, substantially as shown.

HOWARD ORION MILLER.
